COMBINED BILLFOLD, PURSE, AND CARDCASE

Herbert Chase, New York, N. Y., assignor to Bernard Cahn Co. Inc., New York, N. Y., a corporation of New York

Application January 26, 1949, Serial No. 500

Term of patent 7 years

(Cl. D87—3)

To all whom it may concern:

Be it known that I, Herbert Chase, a citizen of the United States, residing at 138-62 62nd Road, city of New York, county of Queens, and State of New York, have invented a new, original, and ornamental Design for a Combined Billfold, Purse, and Cardcase, for which the following is a specification, reference being had to the accompanying drawing, forming part thereof.

Fig. 1 is a plan view of the inside of a combined billfold, purse, and cardcase embodying my new design.

Fig. 2 is a perspective view thereof in a substantially closed position.

Fig. 3 is a perspective view of the inside of the combined article, showing the elements thereof in open positions.

The outside of the article is a plain strip corresponding to the pattern of the lower portion as shown in Figs. 1 and 3, while the purse element is attached top and bottom to the front of the single billfold element as shown in Fig. 3.

I claim:

The ornamental design for a combined billfold, purse, and cardcase, substantially as shown and described.

HERBERT CHASE.
